JAMES BUCHANAN, OF NEW WESTMINSTER, BRITISH COLUMBIA, CANADA

CYLINDER HEAD FOR INTERNAL-COMBUSTION ENGINES

Application filed August 4, 1927. Serial No. 210,637.

My invention relates to improvements in cylinder heads for internal combustion engines the objects of which are to provide means whereby the fuel consumption of the engine is materially reduced and the fuel used is so completely divided as to promote perfect combustion in the compression space of the cylinder. A further and very important object is to provide a means of utilizing the fuel and air required for its combustion for the purpose of cooling the cylinder head.

The invention consists essentially of a cylinder head divided into a plurality of chambers through which air is admitted for cooling purposes and also for admixture to the fuel vapour and for water jacketing of the inlet and exhaust pockets, one of which chambers is provided with a control valve 20 for admitting the air to the inlet valve chamber as will be more fully described in the following specification, in which:—

Fig. 1 is a section taken on the line 1—1 of Figure 2.

Fig. 2 is a section taken on the line 2—2 of Figure 1.

Fig. 3 is a section taken on the line 3—3 of Figure 2.

In the drawings like characters of reference indicate corresponding parts in each figure.

The numeral 1 indicates an engine cylinder having walls 2, a water jacket 3 and upon the upper extremity of such walls a cylinder head, generally indicated by the numeral 4 is secured by studs 5. The cylinder head 4 is preferably formed of two parts 6 and 7 fastened together by studs 8 or other suitable means. The part 6 is provided with a pair of valves 9 and 10 which are operated in any desired manner, the valve 9 being an inlet valve and the valve 10 being an exhaust valve, both of which communicate with the compression space of the cylinder 1.

The numeral 11 indicates a water jacket extending from one side of the head to the other and substantially surrounding the pockets through which the stems 12 and 13 pass, the jacket being provided with ports

14 communicating with the water jacket 3 of the cylinder 1. A chamber 15 is formed in the cylinder head which is provided preferably with a plurality of radiating fins 16 extending upwards to within a short distance of the top wall 17 of the head. This chamber is provided in its side walls 18 with a plurality of apertures 19 through which air is adapted to enter the head, pass over the fins 16 and flow through a passage 20 extending into the head portion 7 which communicates with the inlet valve port 21. The passage 20 is separated from the inlet valve port 21 by a division wall 22 having a valve seat 23 against which an automatically operated conical headed valve 24 is adapted to close. This valve being provided with a conical head permits of the flow of air entering the port 21 to be increased or decreased in direct proportion to the movement of its plunger.

The numeral 25 indicates an exhaust port communicating through the exhaust valve 10 with the cylinder 1, which is suitably connected to the exhaust pipe 26. Under the portion 7 of the cylinder head 4 and formed integrally therewith so that reasonable heat is maintained therein during normal running periods, is a small fuel chamber indicated by the numeral 27. Fuel is supplied to this chamber from a float feed chamber 28, see Figure 3, or other suitable source of supply, through a pipe 29, which fuel naturally rises to a temperature substantially equal to that of the cylinder head portion 7 and becomes highly volatile in consequence, the fuel then flows through a pipe 30 which terminates in a jet 31 extending into the inlet valve port 21, the outlet from which jet is controlled by a threaded valve needle 32 extending downwards through the top wall 17 and into the port 21. Between the jet 31 and the inlet valve 9 a butterfly valve 33 is provided which is actuated in any desired manner.

Having thus described the several parts of my invention I will now briefly explain its function.

The valve 33 is set as desired when starting the engine, the suction stroke of the

engine during which time the inlet valve 9 is open, produces a suction causing the valve 24 to open thereby admitting air across the mouth of the jet 31, withdrawing therefrom a suitable spray of fuel which becomes mixed and broken up into fine division by the air entering the cylinder through the apertures 19, the passage 20 and the inlet valve port 21. As the engine becomes heated to a suitable working condition the heat absorbed by the head 4 is transmitted in part to the air as it passes over the fins 16 and along the various surfaces of the head and its ports and passages, thus causing a more complete division 15 of the fuel drawn off from the jet 31, which results in a greater amount of energy transmitted by the engine from a given quantity of fuel than by the generally accepted method of vaporizing fuel from a carburetor. The engine speed is controlled by the 20 opening or closing of the valve 33 regulating the delivery of fuel to the cylinder head.

It will readily be seen that by this method of heating the fuel to the temperature of the 25 cylinder head and of bringing it to a state of high division with air at a similar temperature, that complete combustion is promoted and in consequence no carbon is deposited upon the cylinder walls even though 30 fuels having a low flash point are used.

What I claim as my invention is:

An engine equipped with a cylinder head formed with an internal air heating chamber and provided with air admission openings placing said chamber in communication with the atmosphere, a port formed in said head and provided with an air inlet for receiving heated air from said chamber, a valve controlling communication between 40 said port and the engine cylinder, a fuel supply conduit communicating with said port at a point between the air inlet and said valve, a water jacket formed in said head in heat interchanging relation with the valve 45 controlled portion of said port whereby said valve is subjected to the cooling influence of both the water jacket and the air flow through the heating chamber, and fins extending from said port to the circumferential wall 50 of the cylinder head and arranged to be traversed by the air passing inwardly through the air admission opening of the air heating chamber formed in said head.

Dated at Vancouver, B. C., this 19th day 55 of July, 1927.

JAMES BUCHANAN.
